COLLAPSIBLE CLOSURES

Walter L. Roy, Saugus, Mass., assignor, by mesne assignments, to Harold B. Neal, Needham, Mass., as trustee

Application August 24, 1953, Serial No. 376,012

9 Claims. (CL. 160—218)

This invention relates to collapsible closures such as blinds, awnings, and the like.

The principal objective of the invention is to provide closures, for such uses, of the type shown in Letters Patent of the United States Reissue 22,311, that are constructed from individual slats, provided with connecting means that enable the closures to be efficiently assembled and that ensure satisfaction in use.

In accordance with the invention, such a closure comprises two series of slats. Each slat has a plurality of spaced pairs of locking portions on one edge and is also provided with a plurality of spaced apertures to enable it to be caught between the locking portions of a slat of the other series. The slats of the two series when thus connected are provided with first and second parallel hinge axes spaced equally from but on opposite sides of a central plane through the length of the blind with any two connected slats being free to swing relative to each other between a collapsed position and an operative position in which the locking portions of one of them bind against opposite faces of the other.

In the accompanying drawings, there is shown an illustrative embodiment of the invention from which these and other of its objectives, novel features, and advantages will be readily apparent.

In the drawings:

Fig. 1 is a face view of a closure in its extended or operative position;

Fig. 2 is an end view of the closure positioned as shown in Fig. 1;

Fig. 3 is a plan view of the closure in its collapsed position;

Fig. 4 is a section, on an increased scale, taken along the indicated lines 4—4 of Fig. 3;

Fig. 5 is a view in perspective of one slat of each series; and

Fig. 6 is a fragmentary edge view of a slat, on an increased scale, showing the disposition of the tabs to facilitate the interconnection of the slats.

In accordance with the invention, there are provided two series of slats, indicated at 10 and 11, respectively. Each slat of both series is shown as having a plurality of projections 12 spaced along its edge 13. Each projection 12 has an open-ended slot 14 of a width greater than the thickness of the stock from which the slats are formed and whose edges are in parallel with the edge 13 and establish a pair of locking portions of which one is in the form of a tab 15.

Each slat is also provided with a plurality of spaced apertures, generally indicated at 16. These apertures are located approximately one-third the distance between the edge defined by the extremity of the projection 12 and the opposite slat edge and each is shown as consisting of three interconnected slots 17, 18, and 19. The slot 17 is disposed at right angles to the edges of the locking portions while the slots 18 and 19 are parallel thereto but preferably of unequal length and establish a tab 20. The length of the slot 17 is equal to the width of the tab 15

and the length of the slot 18 is equal to the width of the web 21 between each tab 15 and the projection 12 of which it is a part.

It will be noted that the tabs 15 and 20 are disposed in opposite directions and, as will be apparent from Fig. 6, they are each curved slightly to expose their extremities above opposite faces of the slat of which they are a part, thus to enable the slat of one series to be disposed on the slat of the other series with the locking tabs 15 of one 10 of them and the tabs 20 of the other of them in alignment. The two slats may be then slid relative to each other so that the locking tabs 15 enter through the slots 17 to the extent permitted by the webs 21. The two slats are thus securely interconnected with one being so caught between the locking portions of the other as to be free to swing from a collapsed position into an operative position in which said locking portions of one slat engage with opposite faces of the other slat to provide a channel of V-shaped section but with the free edge of one slat 20 being disposed beyond the free edge of the other slat.

The slats of the two series are thus connected until the closure is complete. It will be noted from Fig. 2 that the locking portions establish hinge axes and the hinge axis between a slat of one series and the slat of another 25 series caught between its locking portions and the hinge axis between the slat of the first named series and the slat of the other series by whose locking portions it is caught are spaced equally from but on opposite sides of a central plane through the closure.

30 It will also be noted that the slats are so proportioned and the connections between them so located that, when the closure is extended, light is excluded and baffles are provided while insuring adequate ventilation.

It will be noted that each slat includes a marginal free 35 edge part 22 that is disposed at such an angle as to be parallel to said central plane when the closure is extended. While means for so extending the closure are not shown, it will be noted that, adjacent each projection 12, each slat edge 13 is recessed as at 23. In the assembled closure, corresponding recesses 23 align to provide passageways in said central plane as will be apparent from Fig. 3. It will also be noted from Fig. 3, that in the assembled closure, the edges 13 of the slats of the two series are disposed closely adjacent to each other.

40 From the foregoing, it will be apparent that closures in accordance with the invention are easily and securely assembled from individual slats and are well adapted to meet the various requirements of the several uses for which they are intended.

50 What I therefore claim and desire to secure by Letters Patent is:

1. A closure such as a blind, awning, and the like, said closure comprising a plurality of slats arranged in two series, each slat including a plurality of spaced tabs 55 projecting from and disposed in parallel with one edge to define therewith pairs of locking portions and connecting webs, the free ends of said tabs being inclined in the same direction with reference to one face of their slat, each slat also having a plurality of spaced apertures spaced 60 equally from said edge through each of which extends one of the webs of a slat of the other series thus to be caught between the locking portions thereof, said apertures being dimensioned to enable the tabs and webs of a slat of the other series to be entered therethrough when two 65 slats, one from each series, are assembled in face-to-face contact by relative endwise movement with the tabs of one overlapping the tabs of the other and in alignment with and inclined towards the apertures thereof, the slats of the two series being thus connected and provided with 70 first and second parallel hinge axes spaced equally from but on opposite sides of a plane through the length of the blind, and any two thus connected slats being free to

swing relative to each other between a collapsed position and an operative position in which the locking portions of one slat engage opposite faces of the other slat.

2. A closure such as a blind, awning, and the like, said closure comprising a plurality of slats arranged in two series, each slat including a plurality of slats arranged in two series, each slat including a plurality of spaced projections on one edge, each projection having an open-ended slot in parallel with that edge and defining a pair of locking portions, of which one is a tab, and a connecting web, each slat also having a plurality of spaced apertures spaced equally from said edge to receive the tab of a slat of the other series thus to be caught between the locking portions, each aperture defining a tab and having its maximum width and length approximately equal to the width of said projection tabs and webs, respectively, at least one set of tabs having their free ends inclined in the same direction with reference to one face of their slat, the slats of the two series being thus connected and provided with first and second parallel hinge axes spaced equally from but on opposite sides of a plane through the length of the blind, and any two thus connected slats being free to swing relative to each other between a collapsed position and an operative position in which the locking portions of one slat engage opposite faces of the other slat.

3. A closure such as a blind, awning, and the like, said closure comprising a plurality of slats arranged in two series, each slat including a plurality of spaced tabs spaced from and disposed in parallel with one edge to define pairs of locking portions and connecting webs, each slat also having a plurality of spaced slots spaced equally from and parallel to said edge to receive the webs of a slat of the other series thus to be caught between the locking portions thereof, each slat also having a slot in communication with each web receiving slot and defining therewith a tab receiving aperture and an assembly tab the slats of the two series being thus connected and provided with first and second parallel hinge axes spaced equally from but on opposite sides of a plane through the length of the blind, and any two thus connected slats being free to swing relative to each other between a collapsed position and an operative position in which the locking portions of one slat engage opposite faces of the other slat, said slats being dimensioned to enable any pair of connected slats to define a V-shaped channel to shield the hinge axis between one of them and another slat of the other series to which it is connected.

4. A closure such as a blind, awning, and the like, said closure comprising a plurality of slats arranged in two series, each slat including a plurality of spaced tabs projecting from and in parallel with one edge to define a pair of locking portions, each slat also having a plurality of spaced apertures spaced equally from said edge to receive the tabs of a slat of the other series thus to be caught between the locking portions thereof, the slats of the two series being thus connected and provided with first and second parallel hinge axes spaced equally from but on opposite sides of a plane through the length of the blind, and any two thus connected slats being free to swing relative to each other between a collapsed position and an operative position in which the locking portions of one slat engage opposite faces of the other slat, said slats being dimensioned to enable any pair of connected slats to define a V-shaped channel to shield the hinge axis between one of them and the proximate slat of the other series, the other edge of each slat being disposed at such an angle relative thereto as to be parallel to said plane in said operative position.

5. A closure such as a blind, awning, and the like, said closure comprising a plurality of slats arranged in two series, each slat including a plurality of spaced projections on one edge, each projection having an open-ended slot and defining a pair of locking portions and a connecting web, each slat also having a plurality of spaced aper-

tures spaced equally from said edge, each aperture being L-shaped and disposed to provide a slot at right angles to said edge whose width is equal to that of a tab and a slot in parallel with said edge, the length of said last named slot being equal to the width of a web between its tab and said edge, the slats of the two series being thus connected and provided with first and second parallel hinge axes spaced equally from but on opposite sides of a plane through the length of the blind, and any two thus connected slats being free to swing relative to each other between a collapsed position and an operative position in which the locking portions of one slat engage opposite faces of the other slat.

6. A slat for a closure such as a blind, awning, and the like, said slat including a plurality of spaced L-shaped projections on one edge, each presenting a tab spaced from and in parallel with that edge to define therewith a pair of locking portions and a connecting web, and each slat also having a plurality of spaced apertures spaced equally from said edge, each aperture being L-shaped to provide a slot at right angles to said edge whose length is equal to the width of a tab of a like slat and a slot in parallel with that edge whose length is equal to the width of a web, the width of each slot of each aperture being materially less than the width of the part of the L-shaped projection that its other slot is dimensioned to receive.

7. A slat for a closure such as a blind, awning, and the like, said slat including a plurality of spaced, L-shaped projections on one edge, each presenting a tab spaced from and in parallel with that edge to define a pair of locking portions and a web, and each slat also having a plurality of apertures each in the form of three interconnected slots of which one is at right angles to said edge and of a length equal to the width of a tab, another is proximate and parallel to said edge and of a length equal to the width of a web, and the third slot thereof is remote from said edge and parallel to but shorter than the web accommodating slot and serves to establish a tab, said tabs being disposed with their extremities projecting from opposite faces of the slat.

8. A closure such as a blind, awning, and the like, said closure comprising a plurality of members arranged in two series, of which at least one series are slats, each member including a plurality of spaced tabs projecting from and disposed in parallel with one edge to define therewith pairs of locking portions and connecting webs, the free ends of said tabs being inclined in the same direction with reference to one face of their member, each member also having a plurality of spaced apertures spaced equally from said edge through each of which extends one of the webs of a member of the other series thus to be caught between the locking portions thereof, said apertures being dimensioned to enable the tabs and webs of a member of the other series to be entered therethrough when two members, one from each series, are assembled in face-to-face contact by relative endwise movement with the tabs of one overlapping the tabs of the other and in alignment with and inclined towards the apertures thereof, the members of the two series being thus connected and provided with first and second parallel hinge axes spaced equally from but on opposite sides of a plane through the length of the blind, and any two thus connected members being free to swing relative to each other between a collapsed position and an operative position in which the locking portions of one member engage opposite faces of the other member.

9. An interconnecting member for a closure such as a blind, awning, and the like, said member including an L-shaped projection on one edge presenting a tab spaced from and in parallel with that edge to define a pair of locking portions and a web, and each member also having an aperture in the form of three interconnected slots, of which one is at right angles to said edge and of a length equal to the width of a tab, another is proximate

and parallel to said edge and of a length equal to the width of a web, and the third slot thereof is remote from said edge and parallel to but shorter than the web accommodating slot and serves to establish a second tab, 5 said tabs being disposed with their extremities projecting from opposite faces of said member.
